UNITED STATES PATENT OFFICE.

HENRY W. TUTTLE, OF CHICAGO, ILLINOIS.

DESIGN FOR A REFRESHMENT-DISPENSING BOOTH.

Application filed November 19, 1927. Serial No. 24,210. Term of patent 14 years.

To all whom it may concern:

Be it known that I, HENRY W. TUTTLE, a citizen of the United States, residing at Chicago, in the county of Cook and State of Illinois, have invented a certain new, original, and ornamental Design for Refreshment Dispensing Booth, of which the following is a specification, reference being had to the accompanying drawing, forming a part thereof.

The figure is a front perspective view of a refreshment booth, showing my design, the dispensing unit which appears on the top of the shelf and the fragmentary portion of pavement being illustrated in dotted lines.

I claim:

The ornamental design for a refreshment dispensing booth as herein shown.

HENRY W. TUTTLE.
